No. 669,811:

Patented Mar. 12, 1901.

A. A. SPARKS.

CALENDAR.

(Application filed Nov. 20, 1900.)

(No Model.)

UNITED STATES PATENT OFFICE.

ARTHUR ALEXANDER SPARKS, OF SAN FRANCISCO, CALIFORNIA, ASSIGNOR
OF ONE-HALF TO CHARLES C. QUINN, OF SAME PLACE.

CALENDAR.

SPECIFICATION forming part of Letters Patent No. 669,811, dated March 12, 1901.

Application filed November 20, 1900. Serial No. 37,127. (No model.)

To all whom it may concern

Be it known that I, ARTHUR ALEXANDER SPARKS, a citizen of the United States, and a resident of San Francisco, in the county of San Francisco and State of California, have 5 invented a new and Improved Calendar, of which the following is a full, clear, and exact description.

My invention relates to that class of calendars in which a device is provided for indicating at a glance the day of the week and month.

The object of my invention is to furnish a calendar of the above-indicated class which 15 will be simple, strong, easy to operate, and in which the indicator will be securely held against accidental displacement.

To this end my invention consists particularly in certain improvements of the fastening device for the indicator, as will be fully described hereinafter and pointed out in the claims.

Reference is to be had to the accompanying drawings, forming a part of this specification, 25 in which similar characters of reference indicate corresponding parts in all the figures.

Figure 1 is a front elevation of a calendar provided with my improved indicating device. Fig. 2 is a sectional elevation thereof 30 on the line 2 2 of Fig. 1, and Figs. 3, 4, and 5 are fragmentary sectional elevations illustrating other forms of my indicator.

The calendar proper may be of any suitable construction. In Fig. 1 I have shown 35 the ordinary type, in which the calendar consists of a backing or frame A, to which are secured a series of superposed sheets B, each corresponding to one of the twelve months of the year. The invention is, however, also 40 applicable to calendars having a greater or smaller number of sheets. These sheets have the customary spaces B', in which are produced the successive date-numbers. Now in each of these date-spaces B', I provide an individual fastening device for the indicator. 45 As in Figs. 1, 2, and 3, these fastening devices may consist of eyelets C, passing through the sheets B and also, if desired, through the backing A. Incidentally, these eyelets 50 afford a firmer connection between the sheets B than the means usually employed for this

purpose. The indicator (shown in Figs. 1 and 2) consists of a button or head D, having a shank D', adapted to engage the eyelets C. To prevent accidental loss of the indicator 55 and to hold it steady, I connect it with the calendar base or frame A by means of a string, cord, or equivalent element, and preferably said element is constructed with a view of keeping it taut. For this purpose the 60 string E may be elastic, as in Figs. 1, 2, 3, and 5, and in this case one end of the string is fastened to the calendar-frame directly, as at F. Instead of the elastic string I may employ a coiled-wire spring E', as shown in Fig. 65 4, this spring to be attached to the indicator and to the calendar-frame in the same manner as the string E. I may also employ a non-elastic string, the upper portion of which instead of being fixed to the calendar-frame 70 would pass through the latter at a point corresponding to the attaching-point F, and the end of the string would carry a suitable weight and would be allowed to hang behind the calendar-frame A to keep the front run 75 of the string taut. The indicator may be a ball D², as shown in Fig. 3, with a shank D³ to enter the eyelets C.

As shown in Fig. 4, an equivalent of the eyelets consists of holes or perforations C', 80 made in the sheets B and preferably extending into the backing or frame A. The indicator is here made in the shape of a rounded button D⁴, having a shank D⁵.

In Fig. 5 the individual fastening devices 85 consist of pegs or pins C², secured to the backing A and projecting forwardly through perforations C' of the sheets B. The indicator is a disk D⁶, perforated in the center, as at D⁷, to receive the pins C² and having an angular groove for the end of the string or other attaching connection E.

It will be understood that in each case the indicator is placed in the space B' which it is desired to mark prominently, and this indicator is shifted from day to day, being held 95 against accidental displacement by the individual fastening devices provided in each of the day-spaces B'. The connection E keeps the indicator attached to the calendar-frame, 100 and as the said connection is always taut, and in fact under a longitudinal strain, there

is a constant pull exerted upon the indicator, keeping it in firm contact with its holder or fastening device and preventing the indicator from becoming detached. Furthermore, 5 the string or connection E will always be in a straight line, and thus forms a guide for the eye.

Having thus described my invention, I claim as new and desire to secure by Letters 10 Patent—

1. A calendar, having a frame or backing and individual date-spaces, individual holders or fastening devices, one in each of the date-spaces, an indicator adapted to be secured to any one of said fastening devices, 15

and a retractile connection between the indicator and the calendar-frame.

2. A calendar, having a fastening device in each of its date-spaces, an indicator adapted to be secured to any one of the fastening devices, and an elastic cord having one end secured to the indicator and the other to the calendar-frame. 20

In testimony whereof I have signed my name to this specification in the presence of 25 two subscribing witnesses.

ARTHUR ALEXANDER SPARKS.
